CIRCUIT CONTROLLER

Guy Bellows, Jr., and Earnest F. Weiser, Erie, Pa.,
assignors to General Electric Company, a corporation of New York

Application September 2, 1942, Serial No. 456,988

9 Claims. (Cl. 200—87)

Our invention relates to circuit controllers and particularly to means for avoiding false contact operation in electric overload relays subject to violent shock or severe vibration.

The invention has for its principal object the provision of a new and improved substantially shock-proof electric relay.

It is a specific object of our invention to provide new and improved means for positively preventing false operation of the contacts of an electric overload relay due to violent shock or severe vibration.

It is evident that, where essential sources of electric current supply must be kept in operation by means of the apparatus subject to impact and vibration, it is not only highly desirable but absolutely essential that false operation of the overload protective means should not result from the shock or vibration. According to our invention, the contacts of an overload protective relay are rendered substantially shock-proof by mounting the movable contact intermediate the ends of a relatively flexible cantilever spring and providing the relay armature with camming means operable both to apply a high degree of contact pressure when the contacts are engaged and to disengage the contacts while holding the spring against vibration at both sides of the movable contact. Preferably, also, the camming means are so arranged that the relay armature may move at least half way from its circuit closing position to its circuit opening position without disengaging the contacts.

Our invention will be more fully comprehended by referring now to the following detailed specification, taken in conjunction with the accompanying drawing, in which Fig. 1 is a side elevation, partly in section, of an overload relay embodying our invention; Fig. 2 is an end view of the relay of Fig. 1, certain parts being broken away more clearly to illustrate the underlying construction; and Fig. 3 is a fragmentary perspective view of the relay of Figs. 1 and 2.

Referring now to the drawing, the relay chosen for the purpose of illustration is a bus bar overload relay comprising a U-shaped magnetic frame 10 defining an elongated central aperture adapted to receive a bus bar 11 and provided with a pivotally mounted armature 12 to complete a magnetic circuit across the open end of the U-shaped frame. One edge of the armature 12 is beveled to provide a knife edge arranged pivotally to seat at the intersection of one leg of the U-shaped frame 10 and an offset extension 13. The armature is biased to a deenergized or unattracted po-

sition against a non-magnetic stop 14 by means of a tension spring 15 connected between an arm 16 extending from the bight of the frame 10 and a parallel arm 17 extending from the armature 12. One of the parallel arms 16, 17 should be non-magnetic and preferably the arm 17 is of brass. In order to limit lateral vibration of the spring 15 under shock, the spring is closely surrounded centrally by a guide 18 attached to one leg of the magnetic frame 10. Under certain conditions, such as unrestrained lateral vibration of the spring there may be established a torque tending to move the armature 12 to its attracted position. For example, in the relay shown in the drawing, the spring 15 is connected to the armature extension 17 by a pin 19. It will be clear that if the lower end of the pin 19 is moved in a counter-clockwise direction, as by spring oscillation, there will be a tendency to twist the armature 12 to its energized or attracted position.

Bus bar relays of the type described are frequently positioned on one of a plurality of closely adjacent parallel bus bars, so that the adjacent bus very likely will set up a stray flux through the air gap 20 between the armature 12 and the frame 10. This flux may be either aiding or opposing the normal relay actuating flux from the bus bar 11, but in either event it will destroy the calibration of the relay. In order to guard against such

a condition, we provide a magnetic shunt for the air gap 20 in a form of a U-shaped magnetizable member 21 mounted upon the sides of one leg of the frame 10 by means of bolts 22 and spaced therefrom with non-magnetic spacers 23. The armature 12 preferably is separated from the magnetic shunt 21 by a gap greater than the air gap 20 so that the shunt does not carry an appreciable portion of the main relay flux away from the air gap. It will be understood that diminution of the gap defined by the non-magnetic spacer 23 will increase the effectiveness of the magnetic shunt, but will also decrease the pull on the armature 12. Since the relay is calibrated

with the shunt in position the loss of some main flux through the shunt does not effect the calibration, and the shunt serves primarily to lead the stray flux of an adjacent bus bar (not shown), such as a flux indicated by the broken line 24, away from the air gap and directly into the magnetic frame 10. It will be understood that the stray flux of an adjacent bus bar on the other side of the relay will also be carried by the shunt.

The presence of this additional flux in a portion of the magnetic circuit of the relay is not objec-

tionable since the relay may be designed to operate only when it reaches a condition of saturation.

The shock-proof contact mechanism is mounted upon one leg of the magnetic frame 10 within the magnetic shunt 24 and comprises a pair of stationary contact members 30 and a pair of cantilever springs 31 mounted in parallel spaced relation and separated by an insulating spacer 32. Referring particularly to Figs. 1 and 3, the stationary contact members 30 and the springs 31 are clamped together by means of bolts 33 which pass through an insulating shield 34, insulating clamping blocks 35, the springs 31, the insulating spacer 32, and into tapped holes in the fixed contact members 30. This entire assembly is mounted upon the frame 10 by means of bolts 36 which pass through the insulating block 32 between the contact elements and into tapped holes in the adjacent leg of the frame 10. For the purpose of increasing the length of the creepage path between the fixed contacts 30, tubes 37 of insulating material are placed around the cantilever springs 31 and clamped in place between the insulating blocks 32 and 35, the tubes extending some distance along the springs 31 upon either side of the insulating blocks.

The lower ends of the fixed contact members 30 serve as terminal connectors 38, while the lower ends of the contact springs 31 are connected together by a jumper 39. The upper ends of the contact members 30 are provided with fixed contacts 40, while the cantilever springs 31 are provided with cooperating movable contacts 41 attached to the springs intermediate their ends. In this way the cantilever springs and jumper 39 serve as a bridging contact between the fixed contacts 40.

The cantilever springs are self-biased to retain the contacts 41 in engagement with the fixed contacts 40. For the purpose of increasing the contact pressure when the contacts are in engaging position and also for the purpose of separating the contacts, the armature 12 is provided with a T-shaped extension comprising an insulating block 42 and a substantially T-shaped contact actuating member 43. The member 43 may suitably be formed of metal, such as brass, and includes a head portion 44 positioned intermediate the two cantilever springs 31 and extending in substantially parallel spaced relation therewith. It will be understood that the actuating member 43 moves in an arcuate path about the knife edge pivot of the armature 12 when the armature moves between its attracted and unattracted positions. The head portion of the actuating member 43 is provided with three transverse pins 45, 46, and 47 which extend laterally from both sides of the head portion 44 and into sliding engagement with the cantilever springs 31. As clearly shown at Figs 1 and 3, the pins 45 and 46 are spaced apart and engage the outer surfaces of the springs 31 on opposite sides of the movable contacts 41. These pins, 45 and 46, are so positioned that when the contacts are in engagement, they flex the springs 31 on both sides of the movable contacts to increase the contact pressure. For this purpose, also, the free ends of the cantilever springs 31 are provided with camming portions 48 upon which the pin 45 rides in the contact engaging position to increase the flexure of the springs toward the stationary contacts.

The pin 47 is arranged closely adjacent the pin 46 and on the opposite surface of the canti-

lever springs 31. The center of rotation of the armature 12 is so positioned that in moving between its attracted and unattracted positions, it carries the pin 47 along a line oblique to the plane of the contact springs 31 and at a very small acute angle thereto. By referring particularly to Fig. 1, it will be evident that in moving downward along such a line the pin 47 serves to cam the springs 31 away from the fixed contacts 40. In order to permit the contacts to separate under this camming action, the cam portions 48 at the free ends of the contact springs are so shaped that during downward or circuit opening movement of the actuating element 43 the pin 45 rides off of the camming surfaces 48 and permits the free ends of the cantilever springs to move outwardly away from the fixed contacts. By proper positioning of the pins 45, 46, and 47 and proper shaping of the cam elements 48, it will be evident that a substantial movement of the actuating element 43 may be required before the contacts are separated. Preferably, in order to minimize the possibility that the contacts will separate due to shock, about 50% of the contact disengaging movement of the armature should take place before separation of the contacts occurs.

It is believed that the above detailed description of the various parts of our relay and their manner of interconnection will be of itself sufficient for an understanding of the mode of operation, so that no further detailed description of the operation is deemed necessary. By way of summary, however, it may be noted that in the contact separating operation caused by movement of the armature downward from its unattracted to its attracted position, the cantilever springs are at all times firmly held against vibration at both sides of the movable contacts 41. The fact that the pins 45, 46, and 47 are in constant engagement with the cantilever springs at closely spaced points on both sides of the fixed contacts results in a high natural period of vibration for the small section of spring included between the pins 45 and 46. This minimizes the likelihood that the contacts will bounce closed once they are open. It is most essential, however, that the contacts do not separate due to shock when they should remain in their closed position. Such a contingency is doubly guarded against, according to our invention, by the fact that not only must the armature move over half-way toward its contact opening position before the contacts may be separated, but also when the contacts are in their engaging position they are firmly held in this position with an increased contact pressure by both the pins 45 and 46.

While we have illustrated only one preferred embodiment of our invention by way of illustration, many further modifications will undoubtedly occur to those skilled in the art. For example, while we have shown a relay so arranged that its contacts remain engaged to maintain the protected circuit and are separated to disable that circuit, it will be clear that the invention is equally applicable to a relay in which the relay contacts must be held open to maintain the protected circuit and are closed to disable the circuit. We therefore wish to have it understood that we intend in the appended claims to cover all such modifications as fall within the true spirit and scope of our invention.

What we claim as new and desire to secure by Letters Patent of the United States, is:

1. A circuit controller comprising a support, a

fixed contact mounted upon said support, a flexible cantilever spring mounted at one end upon said support, a movable contact connected to said spring intermediate the ends thereof, and actuating means mounted upon said support and having a portion movable obliquely of said spring at a small acute angle thereto to control movement of said movable contact, said actuating member being provided with spaced cam means on opposite sides of said movable contact in constant engagement with said spring to minimize vibration thereof.

2. An overload protective relay comprising a support, a fixed contact mounted upon said support, a flexible cantilever spring having a movable contact mounted intermediate its ends and movable from a circuit maintaining position to a circuit disabling position with respect to said fixed contact, said spring being biased to said circuit maintaining position, an actuating member movable obliquely of said spring to move said spring to said circuit disabling position, and cam means movable with said actuating member in constant engagement with said spring on both sides of said movable contact to minimize vibration of said spring, said cam means being arranged positively to increase the circuit maintaining bias of said spring when said actuating member is in said circuit maintaining position.

3. An overload protective relay comprising a support, a fixed contact mounted upon said support, a flexible cantilever spring mounted at one end upon said support and having a movable contact mounted intermediate said ends, said spring being movable from a circuit maintaining to a circuit disabling position with respect to said fixed contact and being biased to said circuit maintaining position, an actuating member movable obliquely of said spring to move said spring to said circuit disabling position, said actuating member being arranged to complete a substantial proportion of its travel before effecting any significant movement of said movable contact, and cam means mounted upon said actuating member for constant engagement with said spring on both sides of said movable contact positively to increase the circuit maintaining bias of said spring when said actuating member is in its circuit maintaining position.

4. An overload protective relay comprising a support, a fixed contact mounted upon said support, a flexible cantilever spring mounted at one end upon said support and carrying intermediate its ends a movable contact for cooperation with said fixed contact, said spring being biased to retain said contacts in engaging position, and actuating means comprising spaced movable camming means slidably engaging said spring on opposite sides of said movable contact, said camming means being arranged when in a circuit closing position positively to increase the bias of said spring toward said fixed contact and when moved to a circuit opening position to release said additional bias and to separate said contacts.

5. A circuit controller comprising a support, a fixed contact mounted upon said support, a flexible cantilever spring mounted at one end upon said support and having a movable contact fixed intermediate the ends thereof, and actuating means pivotally mounted upon said support and having a portion extending substantially longitudinally of said spring on either side of said movable contact, said portion of said actuating member comprising a pair of adjacent cam ele-

ments engaging said spring on opposite sides thereof, said cam elements being movable obliquely of said spring at a small acute angle thereto to control movement of said movable contact, and second cam means mounted upon said portion of said actuating member for a constant engagement with said cantilever spring at the opposite side of said movable contact, said second cam means being cooperable with said cam elements to hold the included portion of said spring against vibration.

6. A circuit controller comprising a support, a fixed contact mounted upon said support, a flexible cantilever spring mounted at one end upon said support and having a movable contact fixed intermediate the ends thereof, said cantilever spring being biased to retain said movable contact in engagement with said fixed contact, movable actuating means pivotally mounted upon said support and extending substantially perpendicular to said cantilever spring, said actuating member carrying at the end thereof a head portion extending substantially longitudinally of said spring on either side of said movable contact, said head portion of said actuating member being provided with spaced cam means on opposite sides of said movable contact member arranged slidably to engage said spring positively to hold said contacts in engagement and a camming pin intermediate said movable contact and the fixed end of said spring movable obliquely of said spring to cam said movable contact out of engagement with said fixed contact.

7. A circuit controller comprising a support, a fixed contact mounted upon said support, a flexible cantilever spring mounted at one end upon said support and having a movable contact fixed intermediate the ends thereof, said spring being biased to a contact engaging position, an actuating member pivotally mounted upon said support for movement between circuit opening and circuit closing positions, said actuating member including an end portion positioned substantially longitudinally of and adjacent said spring and extending on opposite sides of said movable contact, a camming pin mounted upon said end portion to engage said spring intermediate said movable contact and the fixed end of said spring, said pin being movable slightly obliquely of said spring to cam said movable contact out of engagement with said fixed contact, and cam means at the free end of said spring cooperable with said actuating member to flex said spring in a direction to increase the contact pressure when said actuating member is in said circuit closing position and to release said contact pressure and permit separation of said contacts upon movement of said actuating member toward said circuit opening position.

8. A circuit controller comprising a support, a fixed contact mounted upon said support, a flexible cantilever spring mounted at one end upon said support and having a movable contact fixed intermediate the ends thereof, said spring being biased to a contact engaging position, a movable actuating member pivotally mounted upon said support for movement between circuit closing and circuit opening positions, said actuating member being provided with a head portion extending in substantially parallel spaced relation with said spring on opposite sides of said movable contact, a pair of adjacent pins extending laterally from said head portion to embrace said spring on opposite sides thereof intermediate said movable contact and the fixed end of said

spring, one of said pins being positioned to increase the contact pressure of said spring when said actuating member is in said circuit closing position and both said pins being movable slightly obliquely of said spring to cam said movable contact out of engagement with said fixed contact upon movement of said actuating member to said circuit opening position, a cam element mounted upon the free end of said spring, and a cam follower pin mounted upon said head portion for cooperation with said cam element to increase the contact pressure of said spring in the circuit closing position of said actuating member and to release said additional contact pressure upon movement of said actuating member toward said circuit opening position.

9. In a shock-proof electric circuit overload protective relay of the type comprising a magnetizable frame and an armature therefor movable between circuit closing and circuit opening positions, the combination comprising a support, a fixed contact mounted upon said support, a flexible cantilever spring mounted at one end upon said support and having a movable contact fixed intermediate the ends thereof, said spring being biased to a contact engaging position, means for biasing said armature to said circuit closing position, a contact actuating extension attached to said armature and extending in sub-

stantially parallel spaced relation with said spring on opposite sides of said movable contact, a pair of adjacent camming pins extending laterally from said actuating extension to embrace said spring on opposite sides thereof intermediate said movable contact and the fixed end of said spring, one of said pins being positioned to increase the contact pressure of said spring when said armature is in its circuit closing position and both of said pins being movable slightly obliquely of said spring to cam said movable contact out of engagement with said fixed contact upon movement of said armature to its circuit opening position, a cam element mounted upon the free end of said spring, and a cam follower mounted upon said actuating extension for cooperation with said cam element to increase the contact pressure of said spring in the circuit closing position of said armature and to release said contact pressure upon movement of said armature toward said circuit opening position, said cam portion and said pins being so arranged that said armature must complete a substantial proportion of its travel from its circuit closing position to its circuit opening position before effecting any significant movement of said movable contact.
